UNITED STATES PATENT OFFICE.

FRANK BALSON, OF OMAHA, NEBRASKA.

GUN-STOCK.

No. 894,101.

Specification of Letters Patent.

Patented July 21, 1908.

Application filed October 22, 1907. Serial No. 398,585.

To all whom it may concern:

Be it known that I, FRANK BALSON, a citizen of United States, residing at Omaha, in the county of Douglas and State of Nebraska, 5 have invented certain new and useful Improvements in Gun-Stocks, of which the following is a specification.

My invention relates to improvements in gun stocks, and has for its primary object to 10 provide a gun stock having a series of openings or chambers in the end thereof to form convenient receptacles for tools or implements which it might be desirable to carry with the gun, and to provide a common closure 15 sure for the receptacles, the whole not to mar the appearance of the gun nor interfere with its functions, but on the contrary, rather to add to the attractive appearance of the weapon.

20 Another object of my invention is the provision of an attachment of this character which may be readily mounted in position upon the stock of the gun, which is of simple, durable and inexpensive construction, and 25 which is thoroughly practical in every particular.

With these and other objects in view, my invention consists of a gun stock provided 30 with a series of compartments to receive implements or the like, and a closure to the compartments, the closure serving as the butt plate to the gun.

The invention further consists of a carrying attachment for gun stocks embodying 35 certain other novel features of construction and combination of parts substantially as disclosed herein, and as illustrated in the accompanying drawings, in which:

Figure 1, is a side elevation of a shot-gun 40 stock embodying the features of my invention, parts being broken away and in section to illustrate more clearly the different features of construction. Fig. 2, is an end view of the same with the cover-plate open. Fig. 3, is a 45 broken detail view of the spring catch mechanism for holding the cover closed. Fig. 4, is a detail sectional view of the catch mechanism of the butt plate. Fig. 5, is a broken side elevation showing the invention adapted 50 to the stock of a rifle and an improved form of hunting knife to be used with the rifle 2.

In the drawings: The numeral 1, designates the stock of an ordinary gun which is the same as is usual with the exception that a 55 series of openings or chambers 2, are formed therein in which may be stored the tools or

other accessories generally found useful in the handling of a gun, such as a screw driver, file, shell extractor, cleaning rod or other like devices.

Completely encircling the butt end or rim of the stock, is a metallic band or cap piece 3, which is secured in place by means of screws 4, or other suitable fastenings. The outer edge of this band or butt piece is approximately straight and preferably on a line with the end of the stock, while the inner edge of the butt piece may be curved forwardly as shown, or it may be of any other fanciful design. The butt piece is applied to the stock 70 with its surface level with the surface of the stock so that there are no out-cropping edges to interfere with the ready handling of the gun.

At one of its side edges, the butt piece is 75 provided with a series of ears 5, which are usually three in number and are preferably raised or outstanding from the surface of the butt piece. A common closure is provided for the compartments in the end of the stock 80 which is in the form of a cover or butt plate 6, having ears 7, at one of its side edges to interlock between the ears on the butt piece, the pin or pintle 8, serving to establish the two in hinged relation. The hinge ears on 85 the butt piece and butt plate are preferably formed integral with the respective parts, and as shown in the drawings they may be formed by providing an extension 9, at the edge of each member, then doubling the extension back so as to provide a loop for the 90 passage of the pintle. A flat spring 10, is secured on the inner face of the butt plate near the edge opposite the hinge connection and this spring has a curved end 11, which bears 95 in a recess 12, formed in the inner face of the butt piece, the spring thus normally serving to hold the butt plate open or extended to permit examination of the containers or compartments in the stock. If so desired, instead of dividing the stock into compartments, the stock may be made hollow to provide one large compartment for the storage 100 of different articles. The cover plate is preferably formed with an outwardly bulged or 105 swelled portion 13, at its upper end to assist in holding the gun to the shoulder of the user.

In order to retain the cover or butt plate 110 closed, a hooked lug or latch 14, is provided on the edge of the butt plate opposite the hinge joint, the latch having an inclined abut-

ment face 15, to ride up on the inclined face of the keeper 16. This keeper is carried by the flat spring 17, which is secured on the inner face of the butt piece, the keeper projecting through an opening 18, in the butt piece so as to lie in the path of the latch. A plate or guard 19, is applied to the outer face of the butt piece and the guard is formed with a seat or recess 20, in its outer edge to receive the latch on the butt plate. The latch is thus protected and as it makes smooth close joint with the guard plate all protruding edges are avoided and a smooth ornamental appearance is produced.

15 The guard may be grooved along its edge as at 21, or ornamented in any other suitable manner. A push button 22, projects through an opening in the guard plate and butt piece, the push button having a flanged 20 head at its inner end for engagement with the flat spring 17. Thus by pressing on the push button, the keeper is depressed from engagement with the latch on the butt plate, the butt plate thereby being freed, the release 25 spring carried by the butt plate forces the same open and exposes the compartments or compartment in the gun stock to view.

In Fig. 1, the invention is shown in combination with the stock of a shot gun and in 30 this view a hatchet and shell extractor are indicated as adapted to be seated in the compartments in the stock, as these tools are particularly useful in combination with a gun of this character. On the other hand a 35 hunting knife which might be attached to the end of the barrel would prove a valuable adjunct to a game rifle, and in this connection in Fig. 5, I have shown my improved form of hunting knife as adapted to a rifle. The knife 40 consists of the blade 24, which is preferably double-edged and pointed, the knife being attached by an angular shank portion 25, to the sleeve 26, which is adapted to be slipped over the end of the gun barrel, the sleeve 45 having a notch 27, therein to engage the sight on the barrel. A pair of ears 28, are provided on the lower circumference of the sleeve and pivoted between said ears is the latch 29. A securing stud is provided on 50 the rifle barrel and the latch is formed with an opening 31, to pass over the stud and thereby lock the knife on the end of the barrel. A spring pressed plunger 32, is slidably journaled in the lower side of the sleeve, the 55 said plunger exerting its tension against the rearward extension 33, on the end of the latch, and thereby serving to hold the latch in either the release or locking position with respect to the stud on the gun barrel. A 60 jointed cleaning rod 34, is also shown as

seated in suitable compartments in the stock of the rifle. In smaller rifles where the hunting knife would not be as useful as in the larger ones, the stock may simply be formed with compartments for the reception 65 of cartridges and a cleaning rod, or the like.

From the foregoing description taken in connection with the drawings the operation and advantages of my invention will be readily understood and appreciated and it 70 will be apparent that I have produced an attachment for gun stocks which is entirely practical and desirable and which accomplishes all the results herein set forth as the objects of the invention.

75 I claim:

1. The combination with a gun stock having a series of openings in the butt thereof, a butt piece secured thereto, a butt plate hinged to the butt piece, a spring tending to 80 force the butt plate open, a hooked detent carried by the butt plate, a spring carried by the butt piece, a stud carried thereby and projecting through an opening in the butt piece to engage the detent on the butt plate, 85 and a push button having a headed inner end to engage the spring and release the stud from engagement with the detent.

2. The gun stock having a series of openings therein, a butt piece secured thereto, a 90 butt plate hinged to the butt piece and a spring for forcing the plate normally open, a hooked detent carried by the butt plate, a guard carried by the butt piece recessed to receive the detent, a spring carried by the 95 butt piece, a lug carried by the spring and projecting through an opening in the butt piece to engage the hooked detent and form a keeper to the same, and a headed button seated in the guard and in engagement with 100 the spring to release the keeper from engagement with the detent.

3. In combination with a gun stock, a butt piece secured thereto, a butt plate hinged to the butt piece, a spring exerting tension to 105 force the plate open, a detent carried by the butt plate, a guard on the butt piece to receive the detent, a spring carried by the butt piece, a keeper carried by the spring projecting through an opening in the butt piece to 110 engage the detent, and a button seated in the guard to release the keeper from engagement with the detent.

In testimony whereof I affix my signature in presence of two witnesses.

FRANK BALSON.
